ALFRED HEALD, OF PHILADELPHIA, PENNSYLVANIA, ASSIGNOR TO
McCALLUM, CREASE & SLOAN, OF SAME PLACE.

Design No. 4,493, dated November 29, 1870.

DESIGN FOR A CARPET-PATTERN.

The Schedule referred to in these Letters Patent and making part of the same.

I, ALFRED HEALD, of Philadelphia, county of Philadelphia, State of Pennsylvania, have invented or produced a Design for a Carpet-Pattern, of which the following is a specification.

The figure in the accompanying drawing represents a sufficient of a carpet-pattern to illustrate my design, the main features of which are the square and diamond-shaped tablets A and B, (one-fourth only of which is shown,) with their ornamented borders *e* and *f*, and a bar or stripe, *h*, which forms the outline of both of the tablets A and B, connects the same together, and crosses and breaks the borders *e* and *f*.

The interior of the tablet A is ornamented by bunches, leaves, and flowers, arranged, as clearly shown in the drawing; and in the center of the tablet B is an ornament, *k*, of the character represented, while in the angles between the sides of the said tablet and the border *f* are foliated ornaments, *m*.

The border *f* entirely surrounds the border *e*; and in the same, opposite the corners of the latter, are spots, *p*.

Irrespective of the colors employed, I claim—

1. The design for the tablet A, with its foliated ornaments.
2. The design for the tablet B, with its central ornaments *k*.
3. The design for the ornamented borders *e* and *f* of the tablets A and B.
4. The stripe or bar *h*, forming the outline of both of the tablets A and B, and connecting the same together, as shown and described.
5. The design for the foliated ornaments *m* in the angles between the tablet B and its border *f*.
6. The design for the spots *p*, arranged within the border *f*, as described and represented.
7. The design for the whole pattern, including the tablets A and B, their borders *e* and *f*, the bar *h*, the spots *p*, and the ornamentation described.

In testimony whereof, I have signed my name to this specification in the presence of two subscribing witnesses.

ALFRED HEALD.
